ORCHARD LADDER WITH ADJUSTABLE
PLATFORM AND FRUIT RECEIVING
MEANS

Hubert Tidwell, Wellington, Utah

Application November 26, 1951, Serial No. 258,110

17 Claims. (Cl. 228—1)

1

The present invention relates to a portable apparatus which is constructed and especially designed to assist one in having practical and readily available access to the limbs of a fruit tree while pruning, thinning and picking and collecting fruit, the same being characterized by a safe and reliable self-standing orchard ladder and an arrangement of handy and reliable facilities mounted on the ladder in a manner to provide the user with all necessary equipment to cover an appreciable working area without having to repeatedly dismount and shift the position of the ladder.

Those engaged in the work of picking fruit and attending to pruning and thinning activities are full well aware of the time element and laborious factors involved in connection therewith. Climbing up and down the ladder and changing the position of the same in relation to the branches of the tree is in itself conducive to fatigue and wasted time and effort. Seeking to cope with the currently neglected problem, one objective of the herein disclosed apparatus is to provide an orchard ladder and associated devices which will overcome the likelihood of the ladder tipping over and will consequently relieve the user of the now attending fear of tumbling from the ladder.

It follows therefore that one aspect of the over-all apparatus is to provide an orchard ladder with appropriately constructed and arranged prop means whereby the ladder may be erected on and satisfactorily supported from uneven terrain.

Another difficulty with orchard ladders is that the standing room atop the ladder is undesirably restricted which results in time lost in constantly shifting the ladder to enable the range of activity to meet ever varying work requirements. It is, therefore, another objective of the instant invention to provide means which may be attached to the upper portion of the ladder and which has to do with a platform on which the picker stands, said platform being unique in that it may be raised or lowered and, what is more important, may be adjusted in a horizontal plane about a vertical pivot and retained at given positions in a circular path, making it possible for the picker to rove around and locate himself at varying positions of vantage for full range activities.

A further object of the invention has to do with upright means which is swivelly mounted atop the orchard ladder wherein said means constitutes a support for the picker's platform and

2

is further novel in that it takes the form of a tube, the latter being closed at its bottom and open at its top and providing a convenient elongated receptacle or receiver for collecting and gathering the picked fruit.

A further object of the invention has to do with the aforementioned tubular upright and picker's platform thereon wherein, when the platform is in its low position, the upper portion of the tube projects to an elevation above the same and extends to waist-high level, making it possible for the user to straddle the tube while occupying the platform and to in this manner stabilize himself and to conveniently drop the picked fruit for collection in said tube, the latter having means at its upper end which, if desired, may support an extra bucket to increase the load before descending and emptying the same into transporting containers.

A still further object of the invention pertains to supporting the platform means, the tube and the platform thereon, by way of a novel ladder attachment which is characterized by a bridle-like frame structure slidably harnessed on the ladder stiles and locked in position by existing means on the ladder stiles and having a platform below the first-named platform whereby the user may descend the ladder, detach the tube and empty its contents into a container.

With further reference to the preceding object it is to be pointed out that the frame structure is novel in that it embodies friction brake means characterized by a brake shoe which bridges the ladder stiles, said brake means being brought into braking position by the lower end of the aforementioned tube, the latter being operatively connected with the brake shoe and rockably mounted on the platform of the frame structure so that it becomes in effect an operating lever for applying and controlling the brake to regulate the descent of both platform and loaded tube.

Then, too, novelty is predicated on the use of brake means in the frame structure which is characterized by a yoke which includes the brake shoe and also provides lug-like detents, the latter being associative with projecting heads on the exterior surfaces of the ladder stiles whereby said heads may be employed as keepers for the detents so that when the detents are engaged with the keepers the frame structure is positively retained in an established position on the ladder, either at the median or top portion of the ladder as existing picking conditions require.

Other objects, features and advantages will become more readily apparent from the following

description and the accompanying sheet of illustrative drawings.

In the accompanying drawings wherein like numerals are employed to designate like parts throughout the views:

Figure 1 is a side elevational view of a fragmentary type and with portions appearing in section, showing the complete apparatus and the manner in which the over-all attachment means is used;

Figure 2 is an elevational view of the same observing the structure in a direction from right to left;

Figure 3 is a top plan view showing, in dot-dash lines the approximate manner in which the rotatable picker's platform is selectively moved to desired picking positions;

Figure 4 is a fragmentary view taken on the horizontal line 4-4 of Figure 1, looking in the direction of the arrows;

Figure 5 is a fragmentary sectional and elevational view taken on the vertical line 5-5 of Figure 2, looking in the direction of the arrows;

Figure 6 is a section on the line 6-6 of Figure 5;

Figure 7 is an enlarged fragmentary sectional and elevational view on the line 7-7 of Figure 5;

Figure 8 is an elevational view of one of the details;

Figure 9 is a section on the horizontal line 9-9 of Figure 1;

Figure 10 is a section on the irregular line 10-10 of Figure 9;

Figure 11 is an exaggerated detail view on the horizontal line 11-11 of Figure 10 looking in the direction of the arrows;

Figure 12 is an enlarged detail section on the line 12-12 of Figure 1;

Figure 13 is a view at right angles thereto on the line 13-13 of Figure 12;

Figure 14 is a section on the line 14-14 of Figure 3;

Figure 15 is an elevational view of the picker's platform brace unit;

Figure 16 is a section on the line 16-16 of Figure 15;

Figure 17 is an enlarged cross section on the line 17-17 of Figure 4; and

Figure 18 is a fragmentary detail section showing the manner of attaching a portion of one of the members of the brace unit seen in Figure 15.

Referring now to the drawings by reference numerals and accompanying lead lines, the orchard ladder is denoted by the numeral 20 and comprises converging stiles or rails 22-22 with intervening steps 24. The steps, as best shown in Figure 5, are held in place by horizontal rods 26 passing through the steps and stiles and additional reinforcing rods 28 which underlie the steps and also pass through the stiles. The headed end portions of these are spaced apart in the manner shown in Figure 10 for a purpose to be hereinafter described. Since, however, the heads on rods 28 serve as stops or keepers they are referred to by the numerals 30.

The props for the ladder are denoted by the numerals 32 and 34 and they have their upper ends 36 pivotally connected to the upper portions of the ladder stiles as shown best in Figure 1.

Referring now to Figure 4, the intermediate portions of the ladder stiles are provided with rigid adapter members 36-36 which are provided with substantially L-shaped brackets 38 pivoted in place at 40. These brackets serve to accommodate extensible and retractible stay de-

vices which adjustably connect the props with the ladder. These devices are denoted generally by the numerals 42-42. Each device comprises a link 44 pivoted to the brackets 38 at 46. This link is apertured and slidable through a sleeve 48 on the complementary link 50 which is pivoted at 52 directly to the prop, all as best shown in Figure 4. Link 50 is provided with a spring 54 to which is attached a rectangular collar 56, said collar encircling the sleeve 48 in the manner shown in Figure 17 and said collar being provided with a latching pin 58 which fits selectively into the apertures 60 of the link 44. This arrangement allows the devices 42 to be extended as shown at the right in Figure 4 or contracted as shown at the left in the same figure. It is to be stated here that these details have been described in particular to enable the reader to understand the construction. It is to be understood, however, that these stay devices are not claimed. In other words, insofar as the invention is concerned, it has to do with an orchard ladder with props which are properly connected thereto and which are regulable so as to rigidly support the ladder on uneven terrain.

Attention is now directed to the elevator-like attachment device which is slidably harnessed on the ladder stiles. This, broadly speaking, is in the form of an open frame structure which is characterized in particular by a pair of vertical spaced parallel substantially V-shaped end frames 62-62 (see Fig. 2), said frames being hooked on said stiles and being connected together at 64 and at 66. There is another intermediate bar connection 68 which is a horizontal shelf. This shelf has a keyhole slot therein as shown in Figure 11 with the circular portion of the slot denoted at 70 and the restricted end portion at 72, to be later described. A plate 74 is secured fixedly to the upper end portion of the end frames by attaching ears 76 as shown in Figure 6. This plate has a central circular aperture 78 and said plate serves as a first platform or as more conveniently described, a landing. The shelf 68 is a support for the friction brake means which takes the form of a yoke 80 as shown at 82 in Figure 9. The intermediate portion is a brake shoe 84 and this spans and has friction contact with the edges of the ladder stiles. The lateral arm portions of the yoke 86 are provided with lateral inturned lugs 88 which constitute latching detents. These detents normally engage with the keeper heads 30 in the manner shown in Figure 10 and thus the entire frame structure is held in a set or fixed position. The surfaces 90 are canted or beveled so that when the frame structure is shoved from the lower end of the ladder (not shown) and shifted to an "up" position these surfaces 90 ratchet over the keeper heads 30, that is, they by-pass the keeper heads. In Figure 10, one of the detents is shown engaged with the keeper heads thus locking the frame structure in a set position. When the brake shoe is moved from right to left in Figure 10 the detents are disengaged from the heads 30 and the detents assume the dotted line position whereupon they may ride down in the space between the respective pairs of heads 30 and 92. The brake shoe is provided with an opening 94 of the shape shown in Figure 10, said opening denoted at 95 and this opening registers with the keyhole slot 70 in the shelf. Before discussing the operating connection of the brake shoe it is desired now to take up what is called the rotatable and otherwise adjustable platform means

which is supported from the landing platform 74. As best shown in Figures 1 and 2, this means is characterized by what is called an upright 94 which takes the form of a tube. The upper end is open and provided with a flared mouth 96 carrying a fixed hook 98 which may be used to accommodate the wire bail 100 of the bucket 102. In some instances it is desirable to use a bucket in the picking operation and the bail is engaged with the hook and thus the bucket is supported on the tube 94. The lower end portion of the tube is conical and closed as at 104 and at the juncture of the body portion and cone there is a flange 106 and since the conical portion extends through the opening 78 in the fixed platform 74 a swivel connection for the tube is had. It is to be noted that the body portion of the tube inclines in approximate parallelism with the ladder. The lower end of the conical portion 104 has a sector-shaped rigid extension 105 which is provided with a rib 107 which is projectible as shown in dotted lines into the restricted portion 72 of the keyhole slot to serve as a release. The adjacent portion of the cone, that is, the portion 110 is extended down through the opening means 95 in the brake shoe 84 where it affords an operating connection for the brake shoe using the tube as a sort of a push-pull lever. In doing this the user stands on the landing platform 74 and catches hold the upper end of the tube and manipulates it in a manner to release the detent means 88 from the keeper heads 30 and to simultaneously apply the friction brake shoe to the stiles of the ladder. Therefore, the frame structure may be either locked and held in locked position by the weight of the tube and other devices on the tube and may be released by the same means at which time the brake shoe is applied optionally to allow the frame structure to descend slowly and to carry the user down the ladder with the tube 94 and other structure. The tube obviously serves as a collector or receiver for the picked fruit and it is provided on its interior with flexible baffles or flaps 112 to prevent the fruit from dropping too speedily or heavily into the tube. The entire tube is detachable from the platform 74 and other parts in an obvious manner so as to permit the collected fruit to be emptied into another container (not shown).

The tube is rotatable on platform 74 and may also be rocked in a direction from left to right in Figure 1 at which time the flange 106 constitutes a fulcrum. This is the "lever" operation of the tube for controlling the brake. The conical portion as shown in Figure 7 is provided with aperture means to accommodate an insertable and removable locking pin 114 held in place chain 116 and has a keying lug 118 which fits through the aperture 123 as shown in Figure 7. When the pin is in place the entire tube means is thus fastened to the platform 74. By employing slight play between the pin 114 and platform 74 the latter may be provided with recesses or keeper seats 122 and hence if the tube is turned about a vertical axis the pin 114 rests in one of these seats to hold the tube in an adjusted position, axially speaking.

A picker's platform of suitable size is provided and this is denoted by the numeral 124 in Figures 1 and 3, for example. The platform is detachable and adjustable and hinged. It has arm portions 126 which straddle the tube with upstanding terminals provided with hinging and retaining pins 128 and thence pins fit into depres-

sions 130 indented in the body of the rigid tube. This provides a separable and hinging connection for the platform and allows the platform to extend laterally from the tube where the user straddles the tube and stands on the platform at the same time. This act of straddling the tube gives the user greater purchase while standing on the platform 124 and avoids a sense of falling. The tube extends approximately waist-high so that the picker may drop the apples or other fruit into the receptacle provided by said tube. A brace unit 132 is provided and this is shown in Figure 15 where it includes spaced parallel members 134—134 interconnected by rounds 136—136. The lower ends have outstanding connecting studs 138—138 and these studs are engaged in recesses provided therefor in the furcation portions 140—140 of the platform as shown in Figure 3 and detailed in Figure 14. The upper ends of the members 134 straddle the tube and are provided with inturned studs 142—142 and these studs are releasably engageable in indentations provided therefor at diametrically opposite sides of the tube as shown at 146 in Figure 1. This arrangement also makes the platform 124 foldable which is shown in dotted lines in the same figure and the platform is folded and held up on the hook means 148 so that it will be in an out-of-the-way position when the entire device descends the ladder. By providing other indentations 150 in the upper diametrically opposite side portions of the body of the tube 94 these may be used when the entire platform and suspension means 132 is detached and moved from the low position shown in full lines and inverted and used in the elevated position as shown in dotted lines in the same figure. This makes the platform means liftable and lowerable and increases the range of utility of the tube and platform means. The tube may be provided in one side with a step 152 to help the user to climb up the tube and take a position on the then elevated platform 124 as shown in dotted lines in Figure 1.

The latch pin 114 has the double purpose of securing the tube means swivelly to the landing platform 74 and also constitutes means when coacting with the recesses 122 to lock the tube means and roving platform means 124 in one of the several positions to which the tube means is capable of being turned, thus enabling the platform 124 to be swung in a horizontal plane on a vertical axis and to be placed in varying picking positions to increase the range of activity of the user. The preferred positions are directly over the ladder and props, as is obvious.

The instant invention appreciably increases the usefulness of an orchard ladder. First, the props make the ladder suitable for use on strangely contoured and uneven ground, but what is more important, when the harnessed framework is up the ladder, the user simply steps off of 74 and onto 124 and straddles the tube 94 as shown in phantom lines in Figure 1. The fruit as picked is loaded into 94 and by stepping back on landing 74, the picker's platform can be moved to other positions on tube or folded to an out-of-the-way position, whereupon the detents 88 are released and the brake applied, permitting the picker and his load to "ride" down the ladder and dump the load as he sees fit to do.

In considering the manner of use and operation it will be evident that when the bridle-like frame structure is harnessed atop the ladder as shown in the drawings the same is held in place

by the detents 88 which are then engaged with the uppermost keeper heads 30 and the brake 84 is released (see Fig. 10). Also, the elements 105 and 107 are normally in the full line positions seen in Figs. 10 and 11. Therefore, the tubular upright 94 is free to turn. To accomplish the turning result the picker stands, of course, on the landing platform 74 and catching hold of upright 94 he rotates it until it may be conveniently "locked" through the medium of the pin 114 and recess means 122 as is clear from Fig. 7.

The brake 84 is applied and the detents simultaneously released only when the rib 107 is lined up with and projected into its recess 72, which arrangement makes for requisite safeguarding control. As previously set forth, so long as the rib 107 is out of alignment with the slot restriction 72, the elements 105 and 107 may rotate in the portion 70 of the keyhole-slot. When, however, the user decides to descend the ladder it becomes necessary to line the rib 107 with the restriction 72 whereupon the stated elements 105 and 107 are then permitted to shift from right to left (Fig. 11) and assume the dotted line positions. Now, the detents 88 may be released and the brake shoe 84 may be shifted on shelf 68 (right to left) and applied either lightly or strongly according to the requirements of the picker. A little practice will soon acquaint the picker with the steps which are to be pursued in handling the steps which are to be followed for fully advantageous use.

It is thought that persons skilled in the art to which the invention relates will be able to obtain a clear understanding of the invention after considering the description in connection with the drawings. Therefore, a more lengthy description is regarded as unnecessary.

Minor changes in shape, size and arrangement of details coming within the field of invention claimed may be resorted to in actual practice, if desired.

Having described the invention, what is claimed as new is:

1. For use in enabling one to ascend to a given height above the ground and to then have changeable access to variously located fruit on a fruit tree; a portable apparatus comprising, in combination, a self-standing orchard ladder, platform means above said ladder, and complemental means adjustably connecting the platform means to the ladder in a manner permitting said platform means to be rotatably swung in a horizontal plane about a vertical axis, whereby to permit said platform means to be selectively stationed in predetermined positions of a circular path of movement and to give the user a wide range of support without shifting the position of the ladder relative to the ground, said complemental means embodying, as a component thereof, a receiver in which to gather fruit picked from the tree.

2. The structure defined in claim 1, wherein said ladder is provided with adjustable props to steady the position of the ladder on uneven terrain.

3. The structure defined in claim 1, wherein said complemental means embodies an upright which is adapted to be straddled by the user and which, under the circumstances, affords the user added facilities to stabilize himself while standing on said platform means.

4. The structure defined in claim 3, wherein said upright is tubular and is open at its top

5. and has the additional function of a fruit collecting receiver.

5. For use in enabling one to ascend to a given height above the ground and to then have changeable access to variously located fruit on a fruit tree; a portable apparatus comprising, in combination, a self-standing orchard ladder, an upright swivelly mounted at its lower end atop said ladder and rising to a plane above the ladder, and a picker's platform suspended in a horizontal position from said upright, the latter extending above the platform in a position to be straddled by the picker while standing on the platform.

15. 6. The structure defined in claim 5, wherein said platform is provided with spaced arms straddling said upright and detachably and hingedly joined to said upright, whereby said platform is foldable against and temporarily fastened to said upright whenever necessary or desired.

7. The structure defined in claim 6, wherein said platform is provided with pivotally connected braces which also straddle the upright, said braces being hingedly and detachably joined to said upright, said platform and braces, as a unit, being detachable and shiftable from a low 25 to a high position on the upright, thereby enabling the picker to ascend to a higher level where required, and means on said upright joining said 30 platform and braces thereto when the latter are disposed in said high positions.

8. The structure defined in claim 5, wherein said upright is a tube closed at the bottom and open at the top, whereby said tube constitutes a fruit collecting receiver.

9. For use in enabling one to ascend to a given height above the ground and to then have changeable access to variously located fruit on a fruit tree; a portable apparatus comprising, in combination, a self-standing orchard ladder, a rigid tube closed at its bottom and open at its top, means swivelly and detachably mounting the lower portion of said tube atop said ladder, said means being slidably mounted on the vertical 40 stiles of said ladder, a horizontal picker's platform hingedly and detachably connected to the lower portion of said tube, the upper open end of said tube projecting to a waist-high elevation above said platform being in a position central to the latter and thus adapted to be straddled by the picker when standing on said platform and providing a convenient fruit collecting receptacle and also a satisfactory support for the picker.

10. For use in enabling one to ascend to a given height above the ground and to then have changeable access to variously located fruit on a fruit tree; a portable apparatus comprising, in combination, a self-standing orchard ladder, a first platform embodying means slidably and adjustably mounted on the stiles of said ladder, said platform being thus adapted to descend the ladder in a step-by-step manner with the picker standing thereon, a second fruit picker's platform disposed in a plane above said first platform, a rigid tube open at the top and closed at the bottom, said tube being swivelly and detachably mounted on said first platform and rising to a plane above the latter, and attaching and hinging means operatively connecting said second platform to said tube.

11. For use in enabling one to ascend to a given height above the ground and to then have changeable access to variously located fruit on a fruit tree; a portable apparatus comprising, in combination, a self-standing orchard ladder, a

frame structure slidably mounted on said ladder and adapted to either ascend or descend the ladder, a first platform fixed on said frame structure, upright means swivelly mounted on and rising vertically from said first platform, said upright means being rigid and hollow, and a second platform foldably mounted on said upright means.

12. The structure defined in claim 11, and a friction brake operatively mounted on said frame structure and having releasable detent means cooperable with stops on the stiles of said ladder, and means whereby said upright means serves to apply and release said brake.

13. For use in enabling one to ascend to a given height above the ground and to then have changeable access to variously located fruit on a fruit tree; a portable apparatus comprising, in combination, a self-standing orchard ladder having vertical spaced parallel stiles, a frame structure having vertical spaced parallel end frames 20 slidable up and down on the stiles of said ladder, said end frames having hooked arms slidably harnessed on said stiles, a friction brake shoe operatively mounted on said frame structure and engageable with said stiles, keepers fixed on said 25 stiles, said brake shoe having detents selectively and releasably engageable with said keepers, and a platform carried by said frame structure.

14. The structure defined in claim 13, and means carried by said platform for applying and 30 releasing said brake, said means embodying an upright.

15. The structure defined in claim 13, and means carried by said platform for applying and 35 releasing said brake, said means embodying an upright.

upright, said upright being a rigid tube open at its top and closed at its bottom, said tube being rockably and detachably mounted on said platform.

16. The structure defined in claim 15, and a folding platform pivotally and detachably mounted on said tube.

17. An attachment for an orchard ladder comprising a frame structure having means whereby the same may be slidably harnessed on the stiles of said ladder, and friction brake means operatively mounted on said frame structure and including a projectible and retractible brake shoe adapted to span and engage said stiles, and a platform fixed atop said frame structure, a rigid tube closed at its lower end and open at its upper end, the lower end portion of said tube being swivelly, detachably and pivotally mounted on said platform, the extreme lower end portion of said tube having operating connection with said brake shoe, and a folding platform carried by said tube and situated in a plane above said first-mentioned platform.

HUBERT TIDWELL.
